ATTORNEYS.

UNITED STATES PATENT OFFICE.

HENRY G. SQUIRES, OF PITTSBURG, PENNSYLVANIA.

INK-WELL.

SPECIFICATION forming part of Letters Patent No. 666,362, dated January 22, 1901.

Application filed October 16, 1900. Serial No. 33,203. (No model.)

To all whom it may concern:

Be it known that I, HENRY G. SQUIRES, a citizen of the United States, residing at 118 Seventh street, Pittsburg, in the county of 5 Allegheny and State of Pennsylvania, have invented certain new and useful Improvements in Ink-Wells; and I do declare the following to be a full, clear, and exact description of the invention, such as will enable 10 others skilled in the art to which it appertains to make and use the same, reference being had to the accompanying drawings, and to the letters of reference marked thereon, which form a part of this specification.

15 This invention relates to improvements in ink-wells of that class designed to be permanently supported upon the under side of a desk-top or the like, particularly school-desks, and has for its primary object the provision 20 of a well which may be readily secured in proper position to be within easy access of a user and when not in use may be closed dust-proof and air-tight.

25 The invention contemplates the provision of a suitable case designed to receive and support a slideable fount or drawer and in means for preventing the complete withdrawal of said fount or drawer from the case.

30 The invention also embraces the idea of providing means for locking the fount in closed position in the case.

With such objects in view the invention will 35 be more fully hereinafter described in detail and definitely pointed out in the claims.

35 In the accompanying drawings an embodiment of the invention is illustrated, and when hereinafter referring to the same like letters of reference will refer to corresponding parts in the several views.

40 Figure 1 is a sectional view of the under side of a desk-top of any usual or improved construction, with a well attached in position thereon, the fount being shown in section. Fig. 2 is a side elevation of the well with its 45 fount or drawer withdrawn. Fig. 3 is a vertical sectional view of the same.

Referring more specifically to the drawings, A designates a case, and B a fount or drawer adapted to slide in and out of the case and be 50 retained in open or closed position therein.

The case is provided on its upper surface with suitable perforated lugs or projections

a, through which securing screws or bolts may be passed for attaching the well where desired. The shell and drawer in this instance are formed, respectively, of metal and glass; but it is perfectly obvious that any other material may be employed in place of those mentioned. Likewise in the illustration the case and drawer or fount are seen as 55 substantially rectangular in shape; but this is also immaterial, as any convenient or preferred style or configuration may be employed. To lock the drawer or fount in closed or open position, I provide a thumb-screw C, 60 adapted to pass through the bottom of the case A and impinge against the bottom of the fount, so as to lift the fount and bind the top or open portion thereof against a corked or other suitable compressible surface a' on the 65 interior of the upper portion of the shell. It will be obvious that in closed position the cork or other material will form a tight joint between the case and fount and will render the spilling of the ink impossible. To provide 70 against the cork or other compressible material used being removed by the users, I provide on the front edge of the case, at the top, a downwardly-projecting flange b', adapted, when the fount is lifted by the action of 75 the thumb-screw C, to enter the grooves b made in the fount.

The forward portion of the drawer or fount has a continuous outwardly-projecting flange B', which prevents the pushing of the drawer 85 inwardly too far and covers the edges of the case, rendering it unnecessary to expensively finish or ornament the case, and the rear lower edge of the fount is provided with a downwardly-projecting lug c, designed to travel in 90 the guideway c' of the case and contact with the set-screw D, Fig. 3, to prevent a complete withdrawal of the fount, and when it is necessary to completely withdraw the fount both the set-screw and the thumb-screw can be lowered 95 sufficiently to let the lug on the fount pass and the fount come completely out of the case.

To prevent the complete withdrawal of the respective screws, they are riveted on the inside.

While certain details have been shown and described for carrying the invention into effect, yet it is to be understood that many

changes and alterations may be made without departing in the least from the spirit of the invention.

Having thus described my invention, what 5 I claim as new, and desire to secure by Letters Patent, is—

1. An ink-well comprising a support, a fount slidably mounted therein, means for confining the movement of the fount, a stopper adapted to engage the mouth of the fount when in closed position, and means for forcing the mouth of the fount against the stopper when in such closed position, substantially as described.
- 15 2. An ink-well comprising a case, means for supporting the same, a fount or drawer slidably supported in said case, a lug on said drawer, and means on the case adapted to engage the lug on the drawer to limit the outward movement thereof as and for the purpose set forth.
- 20

3. An ink-well comprising a case, means for supporting the same, a compressible lining on the case, a fount supported by and capable of being withdrawn from said case, and means 25 adapted to engage the bottom of the fount to bind its top against the compressible lining of the casing, as and for the purpose set forth.

4. An ink-well comprising a case, means for supporting the same, a drawer or fount slidably mounted therein, means adapted to lift and lock the drawer when in closed position, and means for limiting the sliding movement of the fount in the case substantially as described.

In testimony whereof I affix my signature in presence of two witnesses.

HENRY G. SQUIRES.
